POWDER DISPENSING SHOEHORN

Joseph J. McDermott, Bronx, N. Y.

Application August 18, 1939, Serial No. 290,771

3 Claims. (Cl. 223—118)

The purpose of this invention is to provide a shoe-horn that ejects powder into the shoe and over the inner sole thereof as it is used, which may also be used in injecting powder into a shoe.

The invention is a shoe-horn having a powder compartment incorporated therein with inlet and outlet openings and means for ejecting powder through the outlet openings independently or as the shoe-horn is used.

It is often desired to use powder on the interior of shoes, and this generally necessitates using a can of powder and shaking it in the shoe, or, where separate devices are used, they are comparatively expensive for the purpose, and, therefore, it is desirable to provide a common shoe-horn with a powder reservoir and openings so that powder may readily be injected in the shoe thereby.

The object of this invention is, therefore, to provide a shoe-horn adapted to eject powder into a shoe.

Another object is to provide a shoe-horn for automatically ejecting powder into the shoe as it is used.

Another object is to provide a shoe-horn from which powder may be ejected as a bellows or the like.

A further object is to provide a shoe-horn having a powder container in combination therewith so that powder may readily be forced through relatively small passages at the tip of the horn.

And a still further object is to provide a powder containing shoe-horn which is of a simple and economical construction.

With these ends in view the invention embodies a shoe-horn having a powder reservoir therein with a passage or passages from the reservoir to the tip of the horn, with openings in the face of the tip communicating with the passages, and with means for creating a pressure therein for ejecting powder therefrom.

Other features and advantages of the invention will appear from the following description taken in connection with the drawing, wherein:

Figure 1 is a view showing a side elevation of a shoe-horn with part broken away illustrating a shoe-horn formed with two layers of material in which the lower ends are hinged together.

Figure 2 is a view showing a front elevation of the shoe-horn shown in Figure 1.

Figure 3 is a detail illustrating a cross-section through the horn shown in Figure 1.

Figure 4 illustrates a rear view of the upper

end of the shoe-horn showing a filling opening therein.

Figure 5 illustrates a shoe-horn of an alternate design in which the powder reservoir is in the form of a bulb at the upper end.

Figure 6 is a detail showing a cross-section through the device shown in Figure 5.

Figure 7 is a view illustrating another modification with the horn portion solid and with a resilient button by which pressure may be created.

Figure 8 is a section through the horn portion of the device shown in Figure 7, showing the relatively small passages therein.

Figure 9 illustrates another modification in which the upper end of the shoe-horn is provided with a bulb made of rubber or the like.

Figure 10 is a detail showing an alternate arrangement in which means is provided for opening and closing the outlet openings.

In the drawing the device is shown as it may be made, wherein numeral 1 illustrates the front portion of a shoe-horn, numeral 2, the rear portion, and numeral 3, a powder reservoir.

In the design illustrated in Figures 1 and 2, parts 1 and 2 are hinged together at the point 4, and the lower end of the part 1 is provided with perforations 5, and it will be noted that, as the two parts are squeezed together when the shoe-horn is placed between the heel of the foot and

heel of the shoe, the part 2 will be moved against the part 1, and any powder in the lower part thereof will be ejected through the perforations 5, and then, when the shoe-horn is withdrawn, additional powder from a reservoir 3 may drop

downward into the horn portion. In this design the edges of the parts 1 and 2 are formed with overlapping flanges 6 and 7, however, it will be understood that the edges may be formed in any manner, or any means may be provided for connecting the edges which will provide a bellows action. In this design the upper end of the part 2 is held under a flange 8 at the upper end of the part 1, permitting a sliding movement between the parts, however it will be understood that the upper edges may be held together in any manner. The upper end of the part 2 may also be provided with a reservoir 3, and this may have a filling opening 9 therein with a cover plate 10 pivotally mounted on a pin 11 and provided with a button 12 limiting the movement thereof, and at the same time making it possible to open the opening 9 for filling.

In the design shown in Figure 5 the lower part or horn portion of the device is somewhat simi-

lar to that shown in Figure 1, except that the edges of the front portion 13, similar to the part 1, are flanged with the edges of the back 14, similar to the part 2, extending under the flanges which are indicated by the numerals 15 and 16, and it will be noted that, as the shoehorn is used, the part 14 being of a springy material will move forward, forcing air and any powder in the space between the compartments outward through the perforations 17 similar to the perforations 5. The part 14 extends upward on the point 18, and the upper end is provided with a reservoir 19 having a filling opening 20 therein, with a cover plate 21 similar to the opening 9 and cover plate 10, and it will be understood that a filling opening of any type or design may be provided. The lower portion of the part 19 is provided with a cross partition 22 having an opening 23 therein, and a spring flap 24 is positioned below the opening forming a valve, with the flap 24 normally extending downward permitting powder to be shaken from the reservoir 19 downward between the parts 13 and 14. However, when the parts are squeezed together, the flap 24 will cover the opening 23 forming a check valve.

In the design shown in Figure 7, the shoehorn is made very similar to that shown in Figure 5, except that the horn portion 25 is solid, and this 30 is provided with small passages 26 extending downward to points adjacent the tip, and the upper bulb portion or reservoir 27 is provided with a button 28, the edges of which may be cemented around an opening 29, and a filling plug 30 threaded in the opposite side, and it will be noted that, as the button 28 is pressed inward, it will force powder from the reservoir 27 downward through the passages 26.

The shoehorn illustrated in Figure 9 is also 40 similar except that the upper portion is made separate and independent, and this is formed of a bulb 31 similar to the bulb of a perfume atomizer, with a narrow neck portion 32 thereof frictionally held over a nipple 33 in the end of the shoehorn 34, the shoehorn 34 being provided with 45 small openings 35 similar to the passages 26, and it will be noted that, as the bulb 31 is squeezed, powder will be forced out of the lower end or tip of the shoehorn.

50 The powder may be contained in a reservoir 36 which may be formed in the shoehorn as shown in the drawing, or attached thereto or provided in combination therewith, and it will be noted that, as air is forced inward by the bulb, the

powder will force downward into the shoehorn and out through the perforations.

In the design shown in Figure 10 the device is provided with an inner sliding member 37 bearing against the inner surface of the front 5 38, and with the upper end 39 extending through the back 40 providing a slide valve. The lower end 41 is adapted to cover openings 42 in the front 38, and the end 39 extends through an opening 43. The opening may be sealed by a 10 sliding washer 44 or any suitable means.

It will be understood that other changes may be made in the construction without departing from the spirit of the invention. One of which changes may be in the use of this device in a 15 shoehorn of any other type or description, another may be in the method of incorporating a powder reservoir in a shoehorn, and still another may be in the use of other means for ejecting powder from the shoehorn.

20 The construction will be readily understood from the foregoing description. In use a shoehorn may be provided of any type or design, and when provided as the bellows type it may be used in the usual manner, and, as it is used, it will automatically inject powder into the shoe below the foot. It can also be used independently to inject powder in the shoe before the foot is placed therein, and may also be used for other 25 purposes.

30 From the foregoing description, it will be noted that it is immaterial how the shoehorn is made or of what material it is made, as any means may be provided in any type of shoehorn for holding powder therein, so that the powder may 35 be ejected therefrom, and the powder may be ejected automatically or manually as may be desired.

Having thus fully described the invention, what I claim as new, and desire to secure by Letters 40 Patent, is:

1. A shoehorn having a hollow thin body, said body having a foot engaging face curved transversely and longitudinally, said face having perforations therein at its lower end, and means for 45 creating pressure within said body for forcing a substance that may be contained therein through said perforations.

2. A device as described in claim 1, having means closing said perforations.

50 3. A device as described in claim 1, having a filling opening therein and a closure therefor.

JOSEPH J. McDERMOTT.
